MATCH PACK AND COVER FOR A CIGARETTE
PACKAGE
Henry C. Dankert, 98 Kings Parkway, Baldwin, N.Y.
Filed Nov. 18, 1963, Ser. No. 324,360
3 Claims. (Cl. 206—48)

This invention relates to a match pack and more particularly to a match pack that is adapted to be utilized as a cigarette package cover and closure.

Match packs are shown to be known in the art in such patents as Beghorn, 1,809,372; Beebe, 1,927,200; Gray, 2,055,721 and Weiss, 2,907,453. The prior art as exemplified by the aforementioned patents were costly and so increased the bulk and size of the cigarette package that they imposed limitations on their own flexibility of use as well as the use of the cigarette packages to which they were affixed.

The desideratum of this invention is to provide a match pack that may be applied to a cigarette package, that need not be formed as an integral part thereof and thereby is capable of being moved relative to the cigarette package and completely removed therefrom when necessary.

Another object of the invention is to provide a match pack which when positioned about a cigarette package serves as a protector for the same. Because of the flexibility of use of the match pack, it can be moved relative to the cigarette package to cover and uncover an opening to permit or prevent the removal or loss of cigarettes from the package.

Still another object of the invention is to provide a match pack that has separate utility, but which, when positioned about a cigarette package, forms a neat, compact covering support therefor.

A further object and feature of the invention resides in the positioning of the matches and their striking heads such that they are enclosed between a side of the match pack and an adjacent side of the cigarette package. This feature obviates the possibility of accidentally igniting the matches unless they are deliberately and forcefully disconnected from the match pack and thereafter purposely struck on the striking surface provided for such function.

Other and further objects of this invention reside in the structures and arrangements hereinabove more fully described with reference to the accompanying drawing in which:

FIG. 1 is a perspective view of the match pack constructed according to the teaching of the invention in a position covering the opening of a cigarette package,

FIG. 2 is a perspective view with the match pack moved relative to the cigarette package to uncover the opening thereof,

FIG. 3 is an edge view of FIG. 1 taken in the direction of lines 3—3, and

FIG. 4 is a cross-sectional view of FIG. 3 taken along lines 4—4.

Referring now to the drawings, the match pack is generally identified by the numeral 10. The match pack 10 is a hollow sleeve-like member having a top wall 12, a bottom wall 14, a rear side wall 16 and a front side wall 18. The hollow member is preferably formed of a relatively stiff yet sufficiently flexible material that will yield slightly under pressures without fracturing, yet of non-stretchable characteristics such that it will retain its shape and form when subjected to forces to which a cigarette package is normally subjected. In practice, it has been found that a vinyl type plastic material is unusually well suited for this purpose. The plastic material may be of a clear or transparent resin thereby permitting the advertisement on the cigarette package to be viewed through the match pack 10 when the same is applied to the cigarette package. Although, at times, the match pack 10

2

has been made with advertising material of its own, printed on its walls.

The front and rear sides 18 and 16 of the match pack 10 serve to supportingly space the top and bottom walls 12 and 14 from each other in an integral continuous endless construction. Mounted on the top wall 12 is a striking surface 20. The striking surface 20 may comprise any suitable abrasive material against which match heads may be struck to cause them to ignite.

Connected to the interior surface of the front side wall 18 are a plurality of matches 22. Each match 22 has a striking head 24 that is located behind and between the lengthwise extent of the side wall 18 from the back edge 26 to the front edge 27 thereof. The matches 22 are positioned in adjacent array extending substantially from the top wall 12 to the bottom wall 14. A sufficient number of matches are provided to at least equal the number of cigarettes in a package. The matches are connected in their adjacent array to the interior surface of the wall 18 by any suitable adhesive means 28. The adhesive means 28 serves to connect a lengthwise portion of each match, at a point thereof that is adjacent to but spaced from the striking heads 24 thereof, to the interior surface of the front side wall 18. The strength of the adhesive means 28 need not be too great and only of sufficient adhering characteristics as to retain the matches 22 against the interior surface of the wall 18 to prevent their accidental disconnection therefrom. The adhesive means 28 is adapted to release when a sufficient manual force or tug is applied to the matches 22 at their exposed ends that extend beyond the pack edge 26 of the front wall 18.

In practice, the match pack 10 has utility by itself. The matches 22, being secured to the interior surface of the wall 18, have their striking heads 24 so hidden that the same cannot be accidentally ignited. However, when it is desired to use one of the matches, the end thereof, extending beyond the back edge 26 of the wall 18, is manually grasped preferably between the thumb and forefinger and pulled in the direction lengthwise away from the back edge 26. A slight pull or tug is sufficient to overcome the connecting force of the adhesive means 28 to disconnect the match 22 from the match pack 10. Thereafter, the striking head of the disconnected match can be struck against the surface 20 causing the same to ignite.

From the foregoing, it should be apparent that when the match pack 10 is positioned about a cigarette package such as that generally identified by the numeral 30, the function of the match pack remains the same. However, its purposes are now enhanced in its ability to perform additional beneficial functions. The soft cigarette package 30 usually has top, bottom, rear and front walls 32, 34, 36 and 38 respectively formed of paper material. Each of these cigarette package walls correspond to and are relatively spaced from each other slightly less than the respective top, bottom, rear and front walls 12 to 18 of the match pack 10. In consequence, the match pack 10 is adapted to receive the cigarette package 30 closely therewithin and to permit the cigarette package to slide relative thereto from a closed position as shown in FIG. 1 to an open position as shown in FIG. 2.

As is usual with cigarette packages of the type 30, an opening 40 is normally made in the top surface 32 thereof to enable cigarettes 42 to be dispensed or withdrawn from the package. In the present invention, the extent of the walls 12 to 18 of the match pack 10 is such that they are materially shorter in length from the front edge 27 to the back edge 26 than that of the corresponding walls of the cigarette package 30. Further, lengthwise distance between the ends of the matches 22 extending beyond the back edge 26 of the front wall 18 to the front edge 27 is less than that of the corresponding front

wall 38 of the cigarette package 30. Thus, when the cigarette package 30 is positioned slidably within the match pack 10, the matches 22, connected at 28 to the interior surface of the front wall 18, are positioned within the confining extent and protection of the wall 38 and snugly between the front wall 18 and the front wall 38 of the cigarette package 30 in the manner as shown in FIGS. 1, 2 and 4 of the drawing. When so positioned, the match heads 24 are fully covered and are prevented from accidental removal or disconnection from the front wall 18. They are also protected against rubbing engagement with any surface that may tend to cause the same to ignite.

When the match pack 10 and the cigarette package 30 are in their relative positions as shown in FIG. 1, the opening 40 of the cigarette package 30 is fully covered by the top wall 12 of the match pack 10 thereby preventing accidental loss or crushing of the cigarettes 42. The walls of the cigarette package 30 corresponding to the encompassing, surrounding walls of the match pack 10 are supportingly engaged thereby and are prevented from accidental crushing or damage. In the position of FIG. 1, it is to be noted that the lengthwise extent between the front edge 42 of the front wall 18 and the external extending ends of the matches 22 is no greater than the lengthwise extent of the adjacent corresponding side wall 38 of the cigarette package 30. In consequence, the whole of the match pack 10 including the extending match ends do not project beyond any part or portion of the wall 38 of the cigarette package. This results in a compact cover for the cigarette package, adding no greater bulk to the cigarette package than the same had when originally manufactured. In addition, the match pack 10 provides the proper support for the walls of a soft cigarette package 30 to prevent damage to the same and its contents.

When it is desired to dispense or withdraw a cigarette 42 from the cigarette package 30, the package 30 and the match pack 10 are moved relative to each other to the position shown in FIG. 2. In this position, the opening 40 of the cigarette package is exposed permitting the withdrawal of the cigarettes 42 therefrom. At the same time, the ends of the matches 22 extending beyond the pack edge 26 of the front wall 18 are now exposed. The user now may simply manually grip any one of the 45 matches between the thumb and forefinger and by tugging slightly on the same, overcome the force of the adhesive 28 thereby disconnecting the match from the wall 18. The match may now be struck on the surface 20 causing its ignition.

While there have been shown and described and pointed out the fundamental novel features of the invention as applied to a preferred embodiment thereof, it will be understood that various omissions and substitutions and changes in the form and details of the device illustrated and in its operation may be made by those skilled in the art, without departing from the spirit of the invention.

It is the intention, therefore, to be limited only as indicated by the scope of the claims appended hereto.

I claim:

1. In combination, a match pack and cigarette package, said match pack comprising a hollow member having a top, a bottom and two sides each integrally connecting said top and bottom together, said top, bottom and sides each being of uniform length, a plurality of matches connected to the interior surface of one of said sides in adjacent array downward therealong substantially from said top to said bottom, each of said matches having an end thereof extending lengthwise beyond an edge of said one side to be manually disconnected from said interior surface, said member defining a sleeve slidably receiving a package of cigarettes therein having an opening in the top thereof through which cigarettes may be withdrawn whereby said top, bottom and sides of said member correspond to respective top, bottom and sides of the cigarette package, said uniform width of said member being less than that of the corresponding respective top, bottom and sides of the cigarette package to enable said member to be slid relative to the cigarette package to a position whereby said uniform width of said member including said extending match ends are positioned between the edges of said corresponding respective side of the cigarette package, each of said matches having a striking head, said striking heads of said matches being positioned adjacent said interior surface of said one side of said member, and adhesive means adjacent the striking head of each match connecting the same to said interior surface whereby, when said sleeve member is moved relative to the cigarette package to cover the opening, said one side and said connected extending match ends are positioned between the edges of the corresponding sides of the cigarette package.

2. A match pack as in claim 1, and a striking surface on said top of said member directed lengthwise therealong against which the striking head of each of said matches may be struck for ignition.

3. In a cigarette package as in claim 1, said hollow member being formed of a relatively flexible material engagingly supporting the corresponding top, sides and bottom of the cigarette package.
